(57) **CLAIM**

The ornamental design for a mobile printer, as shown and described.

DESCRIPTION

FIG. 1 is a top, front and right side perspective view of a mobile printer showing our new design;
 FIG. 2 is a top, front and left side perspective view thereof;
 FIG. 3 is a bottom, front, and right side perspective view thereof;

FIG. 4 is a front elevational view thereof;

FIG. 5 is a rear elevational view thereof;

FIG. 6 is an enlarged right side elevational view thereof;

FIG. 7 is an enlarged left side elevational view thereof;

FIG. 8 is a top plan view thereof; and,

FIG. 9 is a bottom plan view thereof.

The broken lines depict environmental subject matter, are for illustration only and form no part of the claimed design.
